LIGHTING FIXTURE

Marilyn Lewis, Beverly Hills, Calif., assignor to Hamburger Hamlets, Inc.

Filed Dec. 15, 1969, Ser. No. 20,496

Term of patent 14 years

Int. Cl. D26—02

U.S. Cl. D48—4

FIG. 1

FIG. 2

FIG. 4

FIG. 5

FIG. 1 is a front view of a lighting fixture embodying my new design;

FIG. 2 is a side view of the lighting fixture of FIG. 1;

FIG. 3 is an enlarged view of the finial at the top of the light fixture;

FIG. 4 is an enlarged view of a portion of the fringe immediately below the dome of the lighting fixture; and

FIG. 5 is an enlarged view of one of the rosettes on the lighting fixture.

What is claimed is:

The ornamental design for a lighting fixture, as shown.
